CHAIN-DRIVEN RATCHET WRENCH

John D. Strobell, New Haven, Conn.

Application October 2, 1947, Serial No. 777,523

3 Claims. (Cl. 81—57)

1

This invention relates to ratchet tools, especially ratchet wrenches, and has for its object the provision of certain improvements in tools of this character. My invention is particularly concerned with improvements in ratchet wrenches for bolts and nuts and provides a means for the rapid turning thereof to save time, as in the assembling and disassembling of machines.

The usual ratchet wrench is operated by short strokes requiring quite some time in threading or running a loose nut down to, or from, its tight position. My invention provides a means in the handle of the wrench and operable in combination with the ratchet for turning the nut or bolt engaging means (turning head) of the wrench without turning the handle. The wrench of my invention comprises a turning head with a sprocket and an endless roller type chain in the handle of the wrench operable on the sprocket, and a hand-operating means with a ratchet engaging the chain to drive the chain and turning head continuously in one direction by reciprocal strokes of the hand-operating means. The chain and ratchet serve the dual function of turning the head and the nut comparatively rapidly while it is loose and as a ratchet for the final tight setting of the nut.

One of the features of my wrench is that the turning head, which is always operated in one direction by the chain, is preferably symmetrically constructed so that a nut may be run on or off (turned either direction) merely by turning over the wrench. The turning head preferably has an integral sprocket wheel for the chain and engaging holes or lugs extending axially in opposite directions from the sprocket to engage connectors, bars, sockets and the like for connecting with nuts or bolts.

These and other objects of the invention will be better understood after considering the following discussion taken in conjunction with the accompanying drawings, in which:

Fig. 1 is a plan view, with parts broken away, of a socket wrench embodying my invention;

Fig. 2 is a view along line 2—2 of Fig. 1;

Fig. 3 is a sectional view of a modified form of turning head, and

Fig. 4 is an enlarged view of a modified ratchet mechanism of the invention.

The ratchet wrench illustrated in Figs. 1 and 2 comprises a hollow casing or handle 1 formed of two similar flanged pieces 2 and 3 which may be made as by stamping or machining and held together by screws 4, 5 and 6, or other means. Near one end, hole 7 is provided to form bear-

2

ings for the mounting therein of the turning head 8 having an integral sprocket 9. In this form of the invention, the turning head has a square lateral hole 10 for the insertion therein of a connecting bar 11, as shown in broken lines, which may be removable and used for engaging with standard sockets such as the common automotive type sockets.

Near the opposite end of the casing a freely 10 rotatable guide roller 12 is mounted on the shaft or trunnion 13. While I prefer to use a sprocket as shown which is a companion for sprocket 9, I may use any suitable form of pulley. The endless roller type chain 14 is mounted inside 15 the casing and over the sprockets, the center distance of the latter being such as to eliminate slack from the chain. The inside narrow dimension of the space in the casing is slightly more than the overall width of the chain and the inside width of the casing is slightly more than the overall diameter of the chain on the sprockets. Both sprockets are preferably of the same pitch diameter. The flat wide sides of the casing are provided with longitudinal slots 15 and 16 on 20 a plane embracing the axial centers of the sprockets.

A freely movable block or shuttle 20 is mounted within the casing and between the loops of the chain which has lateral extensions 21 and 22 30 slidable in the slots 15 and 16. The main body portion of the shuttle is so proportioned that it will slide freely in the space between the loops of the chain and inside the casing without interference. The projections 21 and 22 not only guide the shuttle on the center line of the two 35 sprockets but provide a convenient means for the attachment of a gripping member such as the sleeve 23 attached to the extensions 21 and 22 by the screws 24. Any suitable hand-operating means may be attached to these extensions.

In the body of the shuttle 20 are provided two square or rectangular recesses 25 and 26 facing opposite sides in which the compression springs 27 and 28 are inserted. These springs bear against and urge outwardly the square or rectangular pawls 30 and 31 so that their beveled ends 32 and 33 enter between the rollers of the chain. The bevels of the pawls may be flat or curved and are faced in opposite directions.

The use of the wrench will be described in 50 connection with the screwing of a nut onto a stud. After the nut has been started on the stud, the socket (not shown) which is attached to the connector 11 in the usual manner is placed over the nut, the handle end 34 of the casing is 55 held in one hand, and the sleeve 23 is grasped in

the other hand and reciprocated back and forth. As the shuttle is moved toward sprocket 12, the pawl 31 engages a roller in the right hand side of the chain (Fig. 1) and causes the chain to translate, turning the two sprockets and consequently the nut. The position of the bevel 32 of pawl 30 is such as to allow the rollers of the left side of the chain to pass by. The nut will be rotated in a clockwise direction.

When the shuttle reaches the end of the slots 15 and 16, its direction is reversed and on the return stroke pawl 30 engages a roller in the left hand side of the chain while pawl 31 allows the chain to pass by. It will be noted that the translation of the chain is always in the same direction, regardless of the direction of travel of the shuttle. Therefore, by reciprocating the shuttle the nut will be run quickly on the thread of the stud.

When the nut can no longer be turned in this manner, either because the thread becomes tight or the nut comes to a bearing, a ratchet action of the wrench is available without the need of making adjustments. It is simply necessary to oscillate the wrench through an arc. The action is as follows: With sprocket 9 stationary and the casing turning in a clockwise direction, the relative motion between the casing and the sprocket tends to cause the chain to run onto the sprocket and as pawl 31 is engaged with a roller of the chain the shuttle will tend to be moved toward the sprocket. However, pawl 30 is also engaged with the chain and as this side of the chain is moving in the opposite direction from that of the other side of the chain it will tend to move the shuttle away from sprocket 9. The result is that the casing, sprocket, chain and shuttle become a locked assembly preventing relative movement between the casing and sprocket and clockwise motion of the casing applies a clockwise torque to the nut. Turning the casing in a counter-clockwise direction reverses the relative motion between the chain and casing, both pawls allowing the chain to pass freely by the shuttle and thus no torque is applied to the nut. The shuttle may be at any point in its stroke during the ratcheting action and it will remain in that position as the action of the two sides of the chain on it are equal and in opposite directions.

Fig. 3 illustrates a modified form of turning head construction. The turning head 40 is mounted in the holes 41, as previously described, and has a unitary member comprising a sprocket 42 similar to sprocket 9 and connector lugs 43 and 44 which are square in cross-sectional area and adaptable to direct engagement with the usual sockets. It is to be understood, of course, that the turning head may comprise any suitable connecting means or shape for engaging tools or articles to be rotated.

Fig. 4 illustrates a modified form of shuttle 50 which reduces the amount of lost motion in the type of shuttle illustrated in Figs. 1 and 2 in which the minimum ratchet angle will be 360° divided by the number of teeth in the sprocket 9. By using two pawls 51, 52 and 53, 54 on each side of the shuttle as in Fig. 4, spaced so that the distance between their engaging beveled surfaces is equal to one or more times the chain pitch plus one-half of the chain pitch, the ratchet angle will be reduced by one-half.

In the action of the wrench as described above and referred to in Fig. 1, the torque is applied in a clockwise direction. If the wrench is turned over so that the socket is applied to the opposite

side from that shown in Fig. 1, its action is reversed so that if applied to a nut the resulting torque action will be counterclockwise to loosen the nut and manipulation of the shuttle will turn the nut in the same direction to run the nut off the stud.

The various parts of the wrench are relatively simple and can be made cheaply. In operation, the wrench effects a material saving in the time required to run nuts on or off bolts or studs. The wrench will operate as a ratchet wrench and requires no adjustment to change the direction of action.

I claim:

15. An improved socket wrench which comprises a handle, a turning head mounted on the handle, a sprocket on said head, an endless chain engaging the sprocket and mounted in the handle, a hand operable shuttle mounted in the handle, at least two pawls in the shuttle urged outwardly in opposite directions by springs, each pawl having a beveled surface facing oppositely from the bevel surface of the other pawl, said pawls being arranged to be inserted between the 20 rollers of the chain by action of the springs, said shuttle being reciprocable to run the chain continuously in one direction by alternate driving engagement of the pawls with links of the chain, and engaging means on both sides of the turning 25 head to run a nut in both directions by turning the wrench over.

2. An improved ratchet wrench which comprises a hollow casing which serves as a handle, a turning head mounted in one end portion of the casing, said turning head being provided with a tool engaging means, a sprocket on the turning head, an endless roller type chain engaging the sprocket and mounted inside the casing, a fixed roller means mounted inside the casing and in a position opposite the turning head for securing the other end of the chain in the casing, guide slots in the casing, a shuttle in the casing and between the loops of the chain, spring pressed pawls in the shuttle extending in opposite directions from each other for engaging rollers of the chain, guide members on the shuttle slidably in the slots for directing the movement of the shuttle along a plane embracing the axis of the turning head, and means for reciprocating the shuttle by hand to drive the chain and turning head continuously in one direction, said pawls serving as ordinary ratchet pawls for operating the turning head by oscillating the handle.

3. A ratchet wrench according to claim 2 which comprises a turning head which has similar engaging means on opposite sides, whereby on turning the wrench over a nut may be run in the opposite direction.
